UNITED STATES PATENT OFFICE

EDWARD T. CONDON, OF NEW YORK, N. Y.

DESIGN FOR A DIRECTIONAL SIGN FOR MOTOR VEHICLES

Application filed September 27, 1932. Serial No. 45,080. Term of patent 7 years.

To all whom it may concern:

Be it known that I, EDWARD T. CONDON, a citizen of the United States, residing in New York, in the county of New York and State of New York, have invented a new, original, and ornamental Design for Directional Sign for Motor Vehicles, of which the following is a specification, reference being had to the accompanying drawing, forming part thereof.

Fig. 1 is a front elevation of a directional sign for motor vehicles, showing my new design.

Fig. 2 is a plan view thereof.

The three casings set forth remain intact with the back-supporting plate, as shown, and the vehicular directional sign indicated is intended to be sold as a single article of manufacture.

I claim:

The ornamental design for a directional sign for motor vehicles, as shown and described.

EDWARD T. CONDON.
